UNITED STATES PATENT OFFICE.

FRANK R. PACKHAM, OF SPRINGFIELD, OHIO, ASSIGNOR TO THE AMERICAN SEEDING MACHINE COMPANY, OF SPRINGFIELD, OHIO, A CORPORATION OF OHIO.

DOUBLE-DISK FURROW-OPENER.

1,079,140.

Specification of Letters Patent.

Patented Nov. 18, 1913.

Application filed January 22, 1913. Serial No. 743,587.

To all whom it may concern:

Be it known that I, FRANK R. PACKHAM, a citizen of the United States, residing at Springfield, in the county of Clark and State of Ohio, have invented certain new and useful Improvements in Double-Disk Furrow-Openers, of which the following is a specification.

This invention relates to improvements in double disk furrow openers of that type particularly adapted for use in connection with grain drills.

One of the objects of the invention is to improve the form of the disk employed in connection with these furrow openers so as to adapt the disk, first, to the more ready application of the scrapers commonly employed in connection with the same; second, to provide more ample and regular room above the hubs of the disks for the installation of certain of the parts of the furrow opening device; and, third, to cheapen and simplify the construction of these disks.

A further object of the invention is to provide an improved bearing for the disks.

A further object of the invention is to provide for improved means for lubricating the bearings of the disks.

A further object of the invention is to simplify the construction and make more effective the operation of devices of this character.

In the accompanying drawings,—Figure 1 is a vertical section taken through the center of a device embodying the improvements. Fig. 2 is a rear elevation of the same. Fig. 3 is a section on the line 3—3 of Fig. 1.

Like parts are represented by similar characters of reference in the several views.

In the said drawings, 1 represents a support for the disks, constructed in the usual way in that it has a forwardly extending drag-bar (not shown) pivotally connected to the machine in connection with which these furrow openers are used. This support 1 is provided in the usual way with a transverse aperture, inclined slightly from the center in opposite directions as shown. Located in this aperture, on each side of the center thereof, is a bearing sleeve, 2, held from turning with relation to the support 1 by a projection 3, extending into an opening or recess, 4, in the support 1. The disks are represented by 5, each of these disks having a centrally-arranged hub, 6, riveted thereto

as shown. Each of the hubs has an inwardly projecting integrally-formed trunnion, 7, journaled in the bearing sleeve, 2, said trunnion being held against lateral movement with respect to said bearing sleeve by a plate, 8, located at the inner end of the trunnion and secured thereto by a rivet, 9; said plate being large enough to embrace the inner end of the bearing sleeve 2, so that said sleeve will be located between 60 said plate and the hub 6 proper of the disk.

The support 1 has an upwardly extending hollow column 10. Within this hollow column is located a hollow oil conduit, 11, having at its lower end inclined projections, 12, which extend into chambers, 13, formed in the upper sides of the bearing sleeves 2; each of these chambers 13 being provided with inclined surfaces as shown so that as the oil conduit 11 is forced downwardly by 75 the set-screw, 14, located at the upper end of the column 10 and coöoperating with an inclined projection 15 on said oil conduit, the tendency will be to draw the disks together so as to adjust them in proper relation with each other, this movement being limited by the contact of the projections 3 with the inner walls of the recesses 4.

The conduit 11 has at its lower end laterally-arranged openings, 16, which communicate with the respective chambers 13 in the bushings or bearing sleeves 2; these chambers 13 being cut entirely through the bushing or sleeve so as to communicate with the trunnion 7 of the disks and thus allow the 90 lubricant to be supplied thereto.

By the construction as thus far described, it will be seen that the bushings or sleeves within which the disk trunnions revolve are non-rotatable and that, therefore, the inclined projections on the lubricant conduit 11 are in contact with non-rotatable parts, which renders this construction an improvement over that shown in my prior Patent No. 745,655, in which the inclined projections on the oil-conduit engage with rotatable parts connected directly with the disk trunnions, as, by the present construction, it will be seen that all wear upon these inclined projections is obviated and a considerable 100 amount of friction overcome.

Heretofore it has been common to employ disks of the concavo-convex form, but in practice difficulty has been encountered in applying suitable scrapers to the convex and 110

concave surfaces of such disks. Attempts have been made to obviate this difficulty by forming the disks with flat circles, such disks being known as "saw-blade disks." 5 These disks, however, are very expensive and difficult to manufacture in a proper manner. To overcome these objections, I construct the disk in the nature of a hollow frustum of a cone so that its inner and 10 outer sides will be formed on straight lines from the central opening thereof to the periphery, as shown in Fig. 1. The method of making this disk consists in first punching the disk in a flat circular form with a central circular opening, heating the same and 15 then drawing the middle portion outwardly, preserving a practically straight line from the center of the disk to the outer periphery. By this construction I am not only enabled 20 to obtain a flat plane for the scrapers on both sides of the disk, but by the drawing of the metal I also relieve all tendency for the metal to buckle or draw crooked, thereby producing at minimum expense a true disk 25 for the purpose intended at a cost far beneath the present "saw-blade" construction. I am enabled also to provide ample and uniform room above the hubs of the disks for the oil-conduit and hollow column surround- 30 ing the same.

In Fig. 2 are shown scrapers, 17, for the exterior of the disk and also scrapers, 18, for the interior thereof, of the usual form illustrating the manner in which the same 35 may be applied to a disk of my improved construction.

Having thus described my invention, I claim:

1. In a double disk furrow opener, a support, oppositely and angularly arranged 40 bushings in said support, said bushings being laterally adjustable in said support but held from rotation therein, a pair of disks, an inwardly-extending angularly-arranged 45 trunnion on each of said disks, said trunnions being rotatably mounted in said bushings but held from lateral movement with respect thereto so as to be movable therewith, and means for simultaneously moving 50 said bushings toward each other.

2. In a double disk furrow opener, a support, oppositely and angularly arranged 55 bushings in said support, said bushings being adjustable laterally in said support but held from rotation therein, disks rotatably mounted in said bushings and movable therewith, each of said bushings having a beveled face, and movable beveled projections coacting with said faces to move said 60 bushings and disks toward each other.

3. In a double disk furrow opener, a support, oppositely and angularly arranged bushings in said support, said bushings being movable laterally in said support but held from rotation therein, disks having 65 trunnions rotatably mounted in said bushings, plates connected with the ends of said trunnions and embracing the inner ends of said bushings to hold said trunnions therein, said bushings having inclined faces, and adjustable inclined projections coacting with 70 said faces to move said bushings and disks toward each other.

4. In a double disk furrow opener, a support, oppositely and angularly arranged 75 bushings in said support, said bushings being movable laterally in said support but held from rotation therein, disks rotatably mounted in said bushings and movable therewith, an oil-conduit, beveled projections upon the end of said conduit, said bushings having inclined faces coacting with 80 said beveled projections, and means for adjusting said oil-conduit whereby said bushings and disks may be moved toward each 85 other, and held in position in said support.

5. In a double disk furrow opener, a support, oppositely and angularly arranged bushings in said support, said bushings being movable laterally in said support but 90 held from rotation therein, disks rotatably mounted in said bushings and movable therewith, each of said bushings having an oil chamber, an adjustable oil-conduit communicating with said oil chambers, and 95 means whereby when said conduit is adjusted, the bushings and disks will be moved toward each other.

6. In a double disk furrow opener, a support, oppositely and angularly arranged 100 bushings in said support movable laterally but held from rotation therein, disk-carrying trunnions rotatably mounted in said bushings and movable therewith, each of said bushings having a chamber communicating with its corresponding trunnion, the inner wall of each of said chambers being formed inclined, an oil-conduit communicating with said chambers, oppositely-arranged 105 beveled projections on the lower end of said oil-conduit coacting with said beveled faces, and means for adjusting said oil-conduit whereby said bushings and trunnions may be moved toward each other.

In testimony whereof, I have hereunto set 115 my hand this 13th day of January, 1913.

FRANK R. PACKHAM.
